UNITED STATES PATENT OFFICE.

GEORGE H. BIRD, OF BROOKLYN, NEW YORK.

SPOOL.

Application filed January 4, 1924. Serial No. 684,810.

To all whom it may concern:

Be it known that I, GEORGE H. BIRD, a citizen of the United States, and a resident of Brooklyn, in the county of Kings and 5 State of New York, have invented new and useful Improvements in Spools, of which the following is a specification.

This invention relates more particularly to spools for receiving ribbon and other 10 narrow fabrics as it is usual to prepare them for sale in dry goods stores and the like.

The objects of the invention are to secure an improved and simplified construction of such a spool, whereby the ribbon may be 15 readily packaged for the market and yet its winding and inspection conveniently provided for; to produce a spool consisting of a core or body portion on which the ribbon is first wound and inspected, and side 20 flanges of sheet material which can be merely pressed into place; to provide grooves at the ends of the core or body portion for receiving said flanges; to provide 25 a spool of this character embodying novel and improved features of construction whereby the usual wooden core, cardboard body on which the ribbon is wound and the side flanges for holding the body 30 on the core can be easily and quickly assembled without gluing or similarly fastening the core in the body, and to obtain other advantages and results as may be brought out by the following description.

35 Referring to the accompanying drawings, in which like numerals of reference indicate the same parts throughout the several views,

Figure 1 is an edge view of one form of my improved spool with ribbon wound 40 thereon;

Figure 2 shows the core or body portion of the spool with its flanges removed;

Figure 3 shows the ribbon wound on the core or body portion and one flange in the 45 act of being applied;

Figure 4 is a side view of the spool, as shown in Figure 1;

Figure 5 is a similar view of the core or 50 body portion alone, as shown in Figure 2;

Figure 6 is an edge view of another form of spool;

Figure 7 is a composite edge view partly 55 in section of the parts of the spool disassembled and in their relative positions;

Figure 8 is a side elevation partly in section of the spool shown in Figure 6;

Figure 9 is a transverse vertical sectional view through the spool;

Figure 10 is an edge elevation of the core; 60 Figure 11 is an end elevation of said core, and

Figure 12 is an end elevation of the caps for securing the flange to the core.

In the specific embodiment of the invention shown in Figures 1 to 5 of said drawings, 1 indicates the core or body portion of my improved spool, which is in general 65 form cylindrical with a hole 2 through it for mounting upon a mandrel or the like for winding and similar purposes. This

core or body portion 1 may be made of any suitable substance, and I have found close grained wood such as thread spools are made of to be very satisfactory. A middle 70 portion of the length of the spool is left cylindrical to receive ribbon of the desired width to be wound thereon, such ribbon being indicated by the reference numeral 3 in the drawings, and grooves 4 are cut into

80 the periphery of the core or body portion 1 at opposite ends of the ribbon-receiving surface 5, these grooves being adapted to receive flanges 6 to lie against the opposite sides of the coil of ribbon, as shown in the 85 drawings, and protect the same. The extremities 7 of the core or body portion 1, outside said grooves 4, 4, are beveled, as shown at 8 in the drawings, to enable the said flanges 6, 6 to be pressed over said extremities 90

7, and said flanges are preferably made of such material that when a central hole 9 is formed in them, smaller than the diameter of the extremity 7 of the core or body portion 1 but as large or larger than the diameter at the bottom of the groove 4, the edges of the flange around said hole 9 will spring over the extremity 7 and snap into place in the 95 groove 4, as illustrated in Figure 3. In

100 said figure the edges 10 of the opening are shown being deflected to snap over the extremity 7 of the core or body portion and snap into the groove 4, and I have found that pasteboard will satisfactorily act in this manner, although I do not wish to restrict myself to any particular material.

When in place the flanges 6, 6 lie close 105 against the sides of the roll of ribbon 3 and protect the same as well as keep it in proper shape.

110 In the specific embodiment of the invention shown in Figures 6-12 of the drawings, 11 indicates a cylindrical core with

a hole 12 through it for mounting upon a mandrel for winding or similar purposes. This core 11 receives axially a drum 13 which is shown hollow and made of pasteboard 5 with central openings 14 at its opposite sides 15 so that it can be pushed onto the core and fit without looseness thereon, its opposite sides being substantially flush with the ends of the core 11. Flanges 16, 16 10 lie against said opposite sides 15 of the drum 13 and against the ends of the core 11 and project beyond the periphery of the drum so as to receive between themselves the ribbon and protect it. Each 15 flange 16 has a central aperture 17 which is somewhat larger than the hole 12 in the core and yet smaller than the outside diameter of said core, and when the flange is disposed in central axial alinement with the 20 core, in manufacture, a cap 18 secures each flange 16 to the core. These caps each having a rim 19 adapted to engage the outer side of the flange 16 and a retaining portion 20 which I have shown as cylindrical 25 which is adapted to pass through the central opening 17 of the flange and be embedded in the end of the core 11. Obviously when this is done the several parts of the spool are secured firmly together and yet 30 the said flanges can be easily applied after the drum has been wound. I have found it very satisfactory to make the flanges and drum of cardboard, the core of wood and the caps of light sheet metal, but it will be 35 understood that any of said parts may be made of any suitable material desired. This form of spool is further advantageous in that such spools may be easily and compactly stacked end to end, the caps 18 being substantially flat so as not to materially 40 project from the ends of the spool as do the ends of the core 1 shown in Figures 1-5 inclusive.

A drum such as the drum 13 also can 45 be utilized with the spool shown in Figures 1-5 inclusive, and in both constructions the flanges 6 and 16 and their separable connection with the respective cores 1 and 11 enable a simple operation in assembling of the parts of the spools and without the use of glue or the like for securing the cores in the drums. One flange 50 6 or 16 may be secured to one end of its corresponding core 1 or 11, the drum carrying the ribbon slipped over the core and then the other flange secured to the other 55 end of the core, so that the core is securely held in the spool and the drum on the core.

Obviously the spool described can be very 60 readily and cheaply made, the ribbon can be quickly and easily wound thereon and is securely held and amply protected by the spool. Various detail modifications could be made in the manufacture of my invention, without departing from the spirit and

scope of the invention, and I do not wish to be understood as restricting myself except as required by the following claims when construed in the light of the prior art. 70

Having thus described the invention, what I claim is:

1. In a spool of the character described, the combination of a drum to receive ribbon or the like and having an axial opening, 75 a core to fit within said opening in the drum, a substantially flat flange applied to each end of said core and engaging the corresponding end of said drum to hold ribbon thereon, and means for securing said flanges 80 directly to said core, whereby the spool may be assembled by securing one of said flanges to one end of said core, slipping the drum with the ribbon thereon endwise over said core or slipping the core into the opening in said drum, and then securing the other of said flanges to the other end of said core. 85

2. In a spool of the character described, the combination of a hollow drum to receive ribbon or the like and having end walls with 90 axial openings, a core to fit within said openings in said drum, a substantially flat flange applied to each end of said core and engaging the corresponding end of said drum to hold ribbon thereon, and means for 95 securing said flanges directly to said core, whereby the spool may be assembled by securing one of said flanges to one end of said core, slipping the drum with the ribbon thereon endwise over said core or slipping the core into the opening in said drum, and then securing the other of said flanges to the other end of said core. 100

3. In a spool of the character described, the combination of a drum to receive ribbon or the like and having an axial opening, 105 a core to fit said opening with one of its ends projecting from the corresponding end of said drum, said projecting end of the core having a peripheral recess, and a pair 110 of flanges secured one to each end of said core, one of said flanges having an axial aperture to spring over the recessed end of said core and into said recess.

4. In a spool of the character described, the combination of a drum to receive ribbon or the like and having an axial opening, a core to fit said opening with one of its ends projecting from the corresponding end of said drum, said projecting end of the core having a circumferential groove adjacent its extremity and its extremity rounded outwardly of said groove, and a pair of flanges secured one to each end of said core, one of 115 said flanges having an aperture with 120 marginal portions to be deflected by said end of the core as the flange is forced thereover and return to their initial position in said groove. 125

5. In a spool of the character described, 130

the combination of a drum to receive ribbon or the like and having an axial opening, a core to fit said opening with one of its ends projecting from the corresponding end of said drum, said projecting end of the core having a circumferential groove adjacent its extremity and its extremity rounded outwardly of said groove, and a pair of flanges secured one to each end of said core, one of said flanges being formed of heavy paper or cardboard and having an axial aperture smaller than said projecting end of the core and adapted to be forced over said end into said groove.

6. A spool of the character described, comprising a straight cylindrical core or body portion substantially uniform in diameter throughout its length having a circumferential groove adjacent one end thereof, and a pair of flanges one secured to each end of said core, one of said flanges being axially apertured to spring over said grooved end of the core and into said groove.

GEORGE H. BIRD.
